UNITED STATES PATENT OFFICE.

GEORGE LEON BARTLETT, OF BOSTON, MASSACHUSETTS.

CLEANING APPLIANCE.

1,351,720.

Specification of Letters Patent. Patented Aug. 31, 1920.

Application filed June 1, 1917. Serial No. 172,303.

To all whom it may concern:

Be it known that I, GEORGE LEON BARTLETT, a citizen of the United States, residing at Boston, in the county of Suffolk and State of Massachusetts, have invented certain new and useful Improvements in Cleaning Appliances, of which the following is a specification.

This invention relates to a device for 10 cleaning automobiles and other articles, and especially those the surfaces of which require care in washing them; and has for one of its objects the provision of washing or wiping means which shall be automatically 15 self cleaning, preferably when in use, and which shall, further, be capable of substantially conforming itself to the surface or surfaces to which it is applied.

Another object of the invention is to so 20 constitute the device with a plurality of these self-cleaning surfaces, that when one of these latter is in use or directly in contact with the article to be cleaned, another of said surfaces is being flushed with cleansing 25 fluid.

Still another object is to so combine the 30 elements of the device that the cleansing fluid supplied thereto not only aids in cleaning the article being washed, together and at the same time serving to remove grit and 35 dirt from the wiping surface or surfaces; but, further,—said fluid itself acts to expand the appliance and to render the wiping surfaces thereof resilient and adaptive 40 to the contour of the surface to be cleansed.

These and other objects of my invention 45 will be hereinafter referred to and the novel combinations of means and elements whereby said objects may be attained will be more particularly pointed out in the claims appended hereto.

In the accompanying drawing which 50 forms a part hereof and in which like reference characters designate like parts throughout the several views, I have exemplified a preferred form of my said device; but as I am aware of various changes and modifications which may be made herein without departing from the spirit of the invention, I 55 desire to be limited only by the scope of said claims.

Referring to the drawing:

Figure 1 is a side elevation of a washing 55 appliance for cleaning automobiles and the like.

Fig. 2 is a vertical longitudinal section of said device, taken on the line II—II of Fig. 1.

Fig. 3 is a transverse section taken on line 60 III—III of Fig. 1.

The device given by way of exemplification preferably comprises a frame 1 of galvanized iron wire or other preferably, although not necessarily, rigid material, which is bent into the form of a substantially 65 closed loop. The wire may be of about No. 11 gage and it is quite important that it be non-rusting in character to prevent rust passing thence through the sides of the bag 2, to the surface being cleansed.

The lower ends 1' of the frame may 70 conveniently be bent over and soldered fast to the inner side of a threaded socket or coupling 3, of brass or the like; this latter preferably being a standard hose coupling. 75 Also soldered fast to said coupling and to said ends, is the base 4' of a stud or nozzle 4, through which the water or other cleansing fluid passes into the bag 2 from a flexible hose 5, the coupling end 5' of which may 80 be screwed in the usual fashion into the socket 3.

I prefer to provide a leather washer 6 in 85 the coupling to form a water tight connection and to tightly bind the mouth of the bag 2 to the neck of the looped frame and stud 4, by a wrapping of wire 7.

The bag 2, of flexible sheet material, is 90 preferably formed of two pieces of tanned sheep-skin or hide from which the wool has not been clipped, or in other words, natural wool-bearing hide; these pieces being somewhat longer and wider over all than the corresponding dimensions of the frame 1, for 95 reasons hereinafter set forth.

The edges of the bag sections are seamed or stitched with tough thread 8 after the frame has been inserted between said sections; the latter having first been washed or treated on their inner sides with hot paraffin oil in which is a considerable proportion of paraffin wax or the like. This treatment is 100 desirable for a number of reasons. In the first place the hide when long subjected to water, without such treatment or the equivalent thereof, is apt to rot. Furthermore, the oil and wax makes said hide more flexible, toughens it and makes it impervious to the washing fluid. Being applied hot, it impregnates the hide, while, of course, it is al- 110

lowed to cool before the sides of the bag are assembled in the manner above described.

An additional advantage of this waxing treatment is that the threads of the seam 8 are themselves automatically waxed when the sides of the bag are being sewed together; so that the thread is toughened and preserved from deterioration from the moisture; while an excellent, practically tight joint is effected.

In the sides of the bag are formed small perforations or apertures such as the holes 9 or slits 10, through which the water or other suitable washing fluid escapes from the interior of the bag into the felt-like mass of long wool filaments which forms the outer sides thereof. These holes, however, are small in size and preferably few in number; there being in the device shown but five water exits or apertures in each side of the bag, or ten in all.

The reason for this is that the bag is intended to distend when the water or the like is turned on, after the device has been connected to the hose; and as it is not desired usually to waste water or to supply it at a high head,—while furthermore the hose should be one which can conveniently be handled,—the provision of but few holes or slits of but small size, permits the device to act in the desired manner.

The distention of the bag or pocket 2 draws the seam 8 in, substantially all around, toward and, preferably, into contact with the frame; reference having been made to the initial spacing of the seam from the frame in the foregoing.

The sides of the bag, hence, being bulged out or fluid-cushioned with water under moderate pressure, become, in effect, resili-ent and are highly adapted to conform to curved or flat surfaces to which they may be applied. Thus, in washing the spokes of a vehicle, this feature becomes of great value, both in that it saves the time of the operator and tends to insure a more perfect cleaning.

Since no metal, or even hard part, what-soever, is presented to the surface to be cleaned, when the coupling 3, preferably spaced as it is from the hides, is grasped as a handle,—the surface, no matter how highly polished, cannot well be scratched. Then, too, even grit or dirt which may be present on such surface is not apt to collect in the wool as it does in the pores of a sponge, on account of the constant movement of water out through the wool, substantially following the filaments thereof.

The fact that the appliance presents a plurality of washing faces is also of advantage, not only because the life of the device is thereby lengthened; but also because while one face is being wiped over the part

to be cleaned and is being supplied with water on that side, the opposite side is being washed free from dirt or grit which may have collected upon it; and yet, owing to the nature of the outer surface of the bag, the water thus acting cannot spout freely out,—to wet the clothes of the operator or even his hand or arm,—but rather seeps, so to speak, quietly out through the wool, flushing the latter from its inner portions outwardly, and the liquid finally passing around the edge of the bag toward the surface being cleaned, whence it escapes.

If the flow of water through the appliance is not sufficiently rapid to suit the user, additional holes can be readily punched out or slits made, and the completely hollow looped frame favors this procedure; while it also, obviously, permits one side of the bag to be pushed directly thereinto to permit the device to accommodate itself to a highly convex surface to be cleansed.

A bag of sheep-skin, such as that described, is most admirably adapted to the purposes in question, and is furthermore comparatively inexpensive, tremendously durable, most easily cleaned, especially when dipped into a bucket of water while at the same time it is flushed from within outwardly, as usual; and it presents a soft, yielding and, in effect, resilient surface which is incomparable for cleaning finely finished varnished surfaces, or the like. Indeed, one of the most desirable features of this cushioned surface is that it may be variably pressed into its frame and yet the pressure to be exerted against the variably contoured surface to be cleaned, is always substantially constant once any material deformation of the flexible water-backed or cushioned sheep-skin face has been effected.

Having thus described my invention, what I claim is:

1. A cleaning appliance comprising in combination a frame, a bag of flexible sheet material secured to and receiving said frame, means to introduce a cleaning fluid into said bag; said sheet material when said bag is filled with said fluid, presenting a filamentary fluid-cushioned surface to the article to be cleaned and being perforate to permit of a flow of the fluid out from said bag into and through the mass of filaments composing said surface, said filaments being substantially incapable of opposing flexure thereof and being so close together that said surface is felt-like and permits said fluid merely to seep therethrough.

2. A cleaning appliance comprising in combination a substantially flat frame, a bag of flexible sheet material secured to and receiving said frame, means to introduce a cleaning fluid into said bag, said sheet material when said bag is filled with said fluid, presenting a filamentary fluid-cushioned

surface to the article to be cleaned and being perforate to permit of a flow of the latter out from said bag into and through the mass of filaments composing said surface, 5 said bag being larger in its overall dimensions than the corresponding parts of the frame therein to permit of its sides being bulged out by the pressure of said fluid, the bag being drawn in toward and pressing 10 against the periphery of said flat frame at such time.

3. A cleaning appliance comprising a two-piece bag, each piece of said bag constituting a side thereof and being of natural - wool - bearing sheep - skin, the wool- 15 bearing sides of said pieces being turned out to form cleaning surfaces and the edges of said pieces being secured together so as to

leave the entire outer cleaning surface of the bag free from any substance which 20 might mar the article to be cleaned, means to introduce a cleaning fluid into said bag to distend the sides thereof, said sides having perforations therein to permit said fluid to escape from the interior of the bag out 25 into the wool upon its outer surface, and a frame within said bag to support said secured edges when the sides are distended in manner aforesaid.

In testimony whereof I have affixed my 30 signature, in the presence of two witnesses.

GEORGE LEON BARTLETT.
